UNITED STATES PATENT OFFICE.

WILLIAM T. SEBLE, OF WYANET, ILLINOIS.

DESIGN FOR A SCOOP.

SPECIFICATION forming part of Design No. 30,292, dated February 28, 1899.

Application filed February 2, 1899. Serial No. 704,295. Term of patent 7 years.

To all whom it may concern:

Be it known that I, WILLIAM T. SEBLE, a citizen of the United States, residing at Wy-
5 net, in the county of Bureau and State of Illi-
nois, have invented and produced a new and
original Design for a Scoop; and I do hereby
declare the following to be a full, clear, and
exact description of the same, reference be-
ing had to the accompanying drawings, form-
10 ing a part thereof.

This invention relates to a new design of
scoop chiefly intended for grocers' use, but
which may be employed for handling com-
modities of every description.

15 The leading feature of the design is a cy-
lindrical body having one end of circular out-
line and the opposite end of elliptical form
and in a plane obliquely disposed to the length
of the body. A loop of oblong form, having
20 its ends rounded and its sides straight and
parallel, is applied to a side of the cylindrical
body and extends lengthwise thereof and is
located opposite the inner end of the elliptical
figure produced by the intersection of the
25 sides of the body with the oblique end thereof.

In the drawings, Figure 1 is a side elevation

of a design for a scoop, illustrating an em-
bodiment of the invention. Fig. 2 is a top
plan view. Fig. 3 is a view of the rear end.

The design comprises a cylindrical body 1, 30
having its rear end 2 of circu' 3 form and in-
tersected by a plane at right angles to the
length or axis of the cylindrical body and
having its front end 3 of elliptical outline and
formed by a plane intersecting the said body 35
and arranged at an oblique angle to the axis
thereof. The loop 4 at one side of the body
is oblong, with its ends rounding and its sides
straight and parallel, and is disposed length-
wise and parallel with the axis of the body 40
and centrally of the elliptical figure 3 and ad-
jacent to the inner or proximal end thereof.

Having thus described the invention, what
is claimed as new is—

The design for a scoop substantially as here- 45
in shown and described.

In testimony whereof I affix my signature
in presence of two witnesses.

WILLIAM T. SEBLE. [L. S.]
